UNITED STATES PATENT OFFICE.

ORSEMEUS L. R. JONES, OF DETROIT, MICHIGAN.

AEROPLANE.

Application filed January 16, 1925. Serial No. 2,828.

This invention relates to aeroplanes, and has for its primary object the construction of an aeroplane that will be more buoyant and at the same time more stable than the planes now in general use.

Another object of this invention is the provision of an aeroplane wing or plane extending lengthwise over the fuselage, said plane tapering from a comparatively wide central portion to a blunt point at the front and a sharper point at the rear.

A further object of this invention is the arrangement of a longitudinal plane with a central keel slightly lower than the side extremities of the plane, whereby wind pressure tends to maintain the plane horizontal, the bow of the plane being inclined upwardly from approximately one-third of the distance of the keel to give the plane a rising or riding tendency.

A further object of this invention is the suspension of the body of the aeroplane below the central keel with connections to the longitudinal wing at opposite sides of the keel and adjacent the side extremities of the wing.

A further object of the invention is the provision of lateral ribs on the longitudinal plane of varying curvature arranged so as to aid in retaining the air currents beneath the plane until passed over, whereby the buoyancy of the aeroplane is enhanced.

Other objects and advantages will be apparent from the following description, wherein reference is made to the accompanying drawings illustrating a preferred embodiment of my invention and wherein similar reference numerals designate similar parts throughout the several views.

40 In the drawings:

Fig. 1 is a side elevation of my improved aeroplane.

Fig. 2 is a front elevation thereof.

45 Fig. 3 is a plan view of the longitudinal plane with parts broken away to show the interior construction thereof.

Fig. 4 is a detail section taken substantially on the line 4—4 of Fig. 3.

Fig. 5 is a detail section taken substantially on the line 5—5 of Fig. 3.

Fig. 6 is a detail section taken substantially on the line 6—6 of Fig. 3.

Fig. 7 is a detail section taken substantially on the line 7—7 of Fig. 3.

Fig. 8 is a detail section taken substantially on the line 8—8 of Fig. 3, and

Fig. 9 is a detail section taken substantially on the line 9—9 of Fig. 3.

Referring now to the drawings, the numeral 5 designates the body of an aeroplane of any desired size and interior design, it being understood that my invention is adaptable for use with various arrangements of body constructions equipped with substantially all engines suitable for aeroplane use.

Accordingly, no attempt has been made to illustrate or describe any particular construction of the body or fuselage, the showing in Figs. 1 and 2 being merely for purposes of exemplification.

In the embodiment shown, I mount the body centrally below the wing or plane 6 and suspend the body from points adjacent the sides of the plane, whereby the weight of the body will aid in maintaining the aeroplane in a substantially horizontal position, and tend to right the aeroplane quickly whenever it assumes a position out of the horizontal.

The bottom of the body 5 is preferably flat to assist in supporting the aeroplane in the air, the flat bottom extending the entire length of the body substantially as shown in Fig. 1 and serving as an auxiliary supporting surface in direct contact with the air currents.

The wing or plane 6 is preferably arranged longitudinally of the body 5 and is formed with a comparatively wide central portion tapering to a blunt point at the front end and a sharper point at the rear.

(Note Fig. 3), the head or bow of the plane being inclined upward from a point about one-third of the distance of the plane, as best illustrated in Fig. 1. The plane 6 comprises a central keel 7 arranged slightly lower than the side extremities of the plane,

whereby it tends to keep the plane right side up, and a plurality of ribs 8 of varying curvature substantially as shown in Figs. 4 to 9 inclusive. The edges of the several ribs 8 are connected by side members 9, and the plane is covered above and below with fabric or other suitable material. The keel 7 extends from the front to the rear of the plane 6 and is curved substantially as shown in Fig. 1 to form the lower line of the plane. This curvature includes a slant downward from the bow 6^a of the plane to the lowermost point 6^b thereof, which point is preferably arranged about one-third of the distance of the plane from the bow, and then a gradual upward incline from the lowermost point 6^b to the rear extremity of the plane. The several ribs 8 are secured at their central portions to the keel 7 and at their edges to the side strips 9. The lower portions of the ribs 8 are graduated in shape from a slight curve adjacent the bow to a comparatively deep curve at the widest portion of the plane, and then gradually resuming a straight shape as they approach the stern of the plane. The purpose of the curvature of the ribs 8 is to secure the maximum buoyancy for the plane, the air currents impinging against the sloped forward portion of the plane to give it a rising or riding tendency and then being retained under the wide central portion of the plane as long as possible. The curvature of the under side of the plane 6 from the central keel toward the sides of the plane also serves to turn the air currents toward the sides of the plane in passage.

The body 5 is arranged below the central keel 7 of the plane 6, and is suspended from the plane by means of struts 10 diverging from the sides of the body to points adjacent the side edges of the plane 6 (note Fig. 2). This suspension of the body at opposite sides of the keel and from points widely separated from the keel tends to maintain the plane in a horizontal position and afford the body a minimum movement during flight. Suitable guy wires 11 may be arranged to aid the struts 10 in supporting the body 5 from the plane 6. The lower extremities of the struts 10 are preferably secured to auxiliary planes 12 fixed upon the sides of the body 5 substantially as shown in Figs. 1 and 2. These auxiliary planes serve the triple purpose of holding the struts and guy wires, of assisting in the mounting and dismounting of passengers, and of increasing the buoyancy of the aeroplane by increasing the supporting surface contacted by the air currents. Any suitable landing gear 13 may be secured upon the body 5, as well as any suitable guiding mechanism 14 for controlling the vertical and horizontal movements of the plane. In Fig. 1 I have illustrated one arrangement of landing gear and guiding

mechanism, but it is to be understood that my invention does not reside in these features of the aeroplane, and so no attempt has been made to show completely operative structures.

While I have illustrated and described the ribs 8 as extending laterally across the keel 7, it is apparent that the desired curvature of the wing 6 may be secured with ribs arranged parallel to the keel 7.

While it will be apparent that the illustrated embodiment of my invention herein disclosed is well calculated to adequately fulfill the objects and advantages primarily stated, it is to be understood that the invention is susceptible to variation, modification and change within the spirit and scope of the subjoined claims.

Having described my invention, I claim:

1. The combination with an aeroplane body, of a plane arranged with its longitudinal axis parallel with that of the body, the plane being formed with a central keel inclined upwardly from a lower central portion toward both the front and rear of the plane, and with cross ribs curving laterally from the keel to the side extremities of the plane, the cross ribs being of different lengths with the longest at the central portion of the keel.

2. The combination with an aeroplane body, of a plane arranged with its longitudinal axis parallel with that of the body, the plane being formed with a central keel inclined upwardly from a lower central portion toward both the front and rear of the plane and with cross ribs curving laterally from the keel to the side extremities of the plane, the curvature and lengths of said ribs differing being longest and deepest at the lower central portion of the plane and with gradually diminishing lengths and curvature toward the front and rear of the plane.

3. In an aeroplane, the combination with a plane having a wide central portion and pointed front and rear portions, of a body suspended from the plane with its longitudinal axis parallel with the longitudinal axis of the plane, the points of attachment of the suspending means with the plane being adjacent the side edges of the plane.

4. In an aeroplane, the combination with a plane having a wide central portion and pointed and front and rear extremities provided with a central keel extending the entire length of the plane and inclined from a lowered central portion upwardly to the front and rear extremities of the plane, of a body arranged beneath the plane with its longitudinal axis in vertical alignment with the central keel of the plane, and connecting members arranged between the sides of the body and the plane, the points of attachment of the suspending members with the plane being adjacent the side edges of the plane.

5. In an aeroplane, the combination with a plane having a wide central portion and pointed front and rear extremities provided with a central keel extending the entire length of the plane and inclined from a lowered central portion upwardly to the front and rear extremities of the plane, of a body arranged beneath the plane with its longitudinal axis in vertical alignment with the

central keel of the plane, and connecting members arranged between the sides of the body and the plane, the body being formed with a flat bottom throughout its entire length and serving as an auxiliary supporting surface in contact with the air currents. **15**

In witness whereof I hereunto set my hand.

ORSEMU^S L. R. JONES.
